(57) **CLAIM**

The ornamental design for a roller cage for paint roller, as
shown and described.

DESCRIPTION

FIG. 1 is a perspective view of a first end of the roller cage
for paint roller;

FIG. 2 is a perspective view of a second end of the roller cage
for paint roller;

FIG. 3 is a perspective view of the first end of the roller cage
for paint roller at an angular rotation marked by section 5-5;
FIG. 4 is a perspective view of the first end of the roller cage
for paint roller at an angular rotation marked by section 6-6;
FIG. 5 is a sectional view of section 5-5 of the roller cage
for paint roller shown in FIG. 3;

FIG. 6 is a sectional view of section 6-6 of the roller cage
for paint roller shown in FIG. 4;

FIG. 7 is a top view of the roller cage for paint roller shown
in FIGS. 3 and 5 which is the same as the bottom, front and
back view of the roller cage for paint roller shown in FIGS.
3 and 5;

FIG. 8 is a top view of the roller cage for paint roller shown
in FIGS. 4 and 6 which is the same as the bottom, front and
back view of the roller cage for paint roller shown in FIGS.
4 and 6;

FIG. 9 is a side view of the second end of the roller cage for
paint roller;

FIG. 10 is a side view of the first end of the roller cage for
paint roller; and,

FIG. 11 is a front view of the roller cage for paint roller.
The stippled lines do not form part of the design.

1 Claim, 4 Drawing Sheets
